UNITED STATES PATENT OFFICE.

JOHN LEE AND CHARLES PEARSON, OF INGERSOLL, ONTARIO, CANADA.

CONTAINER-OPENING DEVICE.

Application filed December 27, 1924. Serial No. 758,470.

To all whom it may concern:

Be it known that we, JOHN LEE and CHARLES PEARSON, both subjects of the King of Great Britain, and both residents of the 5 town of Ingersoll, in the county of Oxford, in the Province of Ontario, Canada, have invented certain new and useful Improvements in Container-Opening Devices, of which the following is the specification.

10 Our invention relates to improvements in container opening devices, and the object of the invention is to devise simple efficient means, easily and quickly operated, for lifting or prying the lid off an air-tight container without in any way detrimentally affecting the container body or lid, and avoiding the production of an air leakage between the container body and lid by the operation of the opener, and the container 15 will therefore remain air proof or sealed when the lid is replaced; and is such a device as will permit the easy replacing of the lid, and by such replacement return automatically the device to its normal position so 20 that it may be again operated to again remove the lid whenever desired, and it consists essentially of the arrangement and construction of parts hereinafter more particularly explained.

25 Fig. 1 is a plan view of a container showing our device applied thereto.

Fig. 2 is a sectional view on line 2—2, Fig. 1, showing the container lid in the closed position.

30 Fig. 3 is a similar view to Fig. 2 showing the lid in the pried up position.

Fig. 4 is a side elevation looking in the direction of arrow, Fig. 1.

35 In the drawings like characters of reference indicate corresponding parts in each figure.

1 indicates a container body provided in proximity to its upper edge by an annular lip 2.

40 3 is a lid, the annular wall 3^x of which fits tightly round the upper edge portion 1^x of the container body 1 against the lip 2 so as to form an air-tight joint.

45 It is well known that it is a very difficult matter to remove the lid from the body of containers containing many classes of material, such as blacking, and with this purpose we have devised the following device:—

50 4 is a projection extending radially from the lid 3 and provided with an internally threaded orifice 4^x.

5 is a threaded stem which is screwed in to the orifice 4^x and is provided at its upper end with an operating handle 6 which may be of any suitable form such as the wing form shown, or extended laterally in crank form or formed in any other way to provide a finger grip so that the threaded stem may be manually turned.

60 The lower end of the stem bears against the annular lip 2 when the cover 3 is in its closed position. The thread of the stem 5 is a steep pitch thread, being preferably at an angle of 27°, although we do not wish to confine ourselves specifically to this angle 65 of pitch. The thread of the orifice 4^x is correspondingly threaded so as to mesh with the thread of the stem. Any angle may be employed approximating the aforesaid pitch so that it does not require much pressure to 70 open the container but is sufficiently steep to produce rotary movement of the stem when end pressure is applied, whereby the stem is turned and moved longitudinally 75 back to its normal position. The lower end of the stem is slightly riveted over, as indicated at 5^x, to prevent its complete withdrawal from the orifice 4^x so that there will be no danger of it becoming detached from 80 the container and lost.

85 When it is desired to open the container, all that it is necessary to do is to turn the stem a half turn so that such stem, by means of its thread, is carried quickly downward against the lip 2, thereby exerting an upward force upon the lid to pry it at the side upon which the stem is located upward free of the upper edge portion 1^x of the container body into the position shown in Fig. 3.

90 In this position air is permitted to enter 95 the container and thereby relieve the suction and permit the easy removal of the lid from the container body.

95 When it is desired to close the container by replacing the lid, all that it is necessary 100 to do is to return the lid to the position shown in Fig. 3, and then by exerting a downward pressure upon the lid, an upward pressure of the lip 2 against the stem is produced, such pressure by means of the 105 steep pitch of the thread of the stem 5, causing the stem to turn in the internally threaded orifice 4^x so that such stem is carried longitudinally back to the normal position shown in Fig. 2, as the lid travels down 110 to its closed position, and thereby again producing a sealed joint between the lid and

the container body which will be absolutely air-tight.

Although we have shown our device as applied to a container for blacking, it will of course be understood that it is applicable to any air-tight container, the lid or cover of which is removable, and is particularly adapted to all sheet metal containers of this type, such as are used for containing various commodities such as honey, syrup, lard or paint.

What we claim as our invention is:

1. In an air-tight container, the combination with the container body provided with an annular lip, of a lid fitting around the upper edge of the container body against the aforesaid lip, a projection extending radially from the lid having a threaded orifice therein, and a threaded stem fitting within the orifice and engaging the thread thereof and bearing at its lower end against the lip, the thread being of such a pitch as to produce turning movement within the afore-

said orifice when pressure is exerted against the lower end of the stem, whereby the stem is forced back to its normal position, and means at the upper end of the stem for manually turning the same to carry the stem downward against the aforesaid lip. 25

2. In an air-tight container, the combination with the container body provided with an annular lip extending outward adjacent its upper edge, of a projection extending radially from the lid, a threaded rotatable stem longitudinally movable within the projection and having a slight enlargement at the lower end of the stem to prevent its complete withdrawal, said stem being adapted to be forced by manual pressure in a direction parallel with its axis longitudinally 40 against the lip for forcing the container lid upward, said stem being adapted to return to its normal position by downward manual pressure upon the lid. 30
